W. I. STIMPSON ET AL

FILLING CARRIER RECEIVER FOR REPLENISHING LOOMS

Filed Feb. 12, 1926

UNITED STATES PATENT OFFICE.

WALLACE I. STIMPSON AND ALFRED E. STAFFORD, OF HOPEDALE, MASSACHUSETTS,
ASSIGNORS TO DRAPER CORPORATION, OF HOPEDALE, MASSACHUSETTS, A COR-
PORATION OF MAINE.

FILLING-CARRIER RECEIVER FOR REPLENISHING LOOMS.

Application filed February 12, 1926. Serial No. 87,779.

This invention relates to filling carrier receivers for catching the filling carriers as they are ejected from the loom upon replenishment of filling.

8 It is now the common practice to provide filling replenishing looms with a receiver or can into which the filling carriers are thrown upon replenishment of filling. It sometimes happens that a filling carrier is 10 ejected from a shuttle while still containing a working supply of filling, and in such case the filling carrier may be returned to the hopper to be again used in the loom.

15 In weaving fabrics with certain kinds of filling, the impact of the ejected filling carrier against other filling carriers already in the can or receiver, frequently injures the filling on the ejected filling carrier to such an extent that even if the carrier contains 20 a working supply of filling, it may not be practical to return the filling carrier to the hopper and weave in the injured filling. This is particularly observable in connection with fine filling, such, for instance, as 25 silk, artificial silk and the like, and one of the objects of the present invention is to provide a filling carrier receiver which will avoid injury to the filling on a filling carrier when it is ejected from the loom, so 30 that should the filling carrier contain a working supply of filling, it may be returned to the hopper and the filling thereon be subsequently woven into the cloth.

35 The invention and novel features and new combination of parts will best be made clear from the following description and the accompanying drawings of one good form thereof.

In the drawings:—

40 Fig. 1 is a perspective view at the replenishing side of a filling replenishing loom, showing a filling carrier receiver or can into which the ejected filling carriers are thrown from time to time;

45 Fig. 2 is an enlarged detail perspective view showing the filling carrier receiver provided with the present invention; and

50 Fig. 3 is a vertical section of a filling carrier receiver containing the present invention.

The loom frame 1 may be of usual con-

struction and have mounted thereon a hopper 2 containing filling carriers 3 containing filling for use in a shuttle, and such hopper and its associated parts may be of any usual 55 character.

The lay 4 is provided with the usual shuttle box at the filling replenishing side of the loom for the reception of the shuttle 5, and mounted on the loom frame or a 60 bracket secured thereto is the usual transferring mechanism for transferring the filling carrier from the hopper to the shuttle, and simultaneously ejecting the filling carrier previously in the shuttle. The transferring mechanism may comprise the usual 65 transferrer 6 having the downwardly extending arm 7 to which is pivotally mounted the dog 8 adapted to be engaged by a bunter 9 on the lay to effect the transfer. 70 These parts may be as usual.

The shuttle 5 may also be of the usual filling replenishing type and it, as well as the bottom of the shuttle box, may also, as usual, be provided with an opening through 75 which the ejected filling carrier may pass downwardly into the filling carrier receiver beneath. It may be desirable at times to employ a chute 10 down which the ejected filling carrier may be guided on its way to 80 the receiver.

The present invention is more especially directed to the filling carrier receiver, which is located at the replenishing side of the loom in position to receive the filling carriers 85 as they are ejected from the shuttle.

The filling carrier receiver comprises a receptacle 11, the front wall 12 of which is higher than the back wall 13, and the two walls are connected by the side plates 14 90 and by the bottom plate 15. The front wall 12 is carried upwardly beyond the top of the side walls to provide a hand-grip 16, and such receptacle or receiver as thus far described may be of usual construction. 95

When a filling carrier is ejected from the shuttle during replenishment of filling, it is thrown forcefully in a downward direction through the chute 10 into the receiver or can beneath, and should at such times the filling 100 carrier contain a working supply of filling, such filling is liable to be injured by impact.

against other filling carriers already in the receiver, or, indeed, against any hard surface.

In accordance with the present invention, 5 the filling carrier receiver is provided with a flexible apron preferably located near the lower part and within the receiver to divide it into an upper and lower compartment and the apron is so mounted in the receiver 10 that upon impact of a filling carrier upon the apron, it will flex and offer a yielding surface contact with the filling on the filling carrier or bobbin.

The flexible receiving apron 17 may be 15 formed of a suitable fabric, such, for instance, as canvas or the like, and the front end portion of the apron 17 is secured in the receiver adjacent the front wall thereof, while the rear end portion of the receiving 20 apron is yieldingly held in the receiver nearer the back wall thereof.

In the present instance of the invention, the filling carrier receiver has extending between the sides 14 thereof a bar or rod 18 25 which serves as a means for securing the flexible receiving apron near the front wall of the receiver. Extending between the sides 14 of the receiver is another support which may be conveniently constituted as a 30 bar or rod 19 over which the body portion of the flexible receiving apron 17 passes and upon which it rests. The free end of the flexible receiving apron is under the influence of means for yieldingly maintaining 35 the apron in its carrier receiving position such that upon impact of a filling carrier thereon, the apron may flex, as indicated by dotted lines in Fig. 3. As means for thus maintaining the apron in the position described for the performance of its flexing 40 function, a down-hanging portion 20 of the apron may be connected to a weight 21 secured to the lower end of the apron, the construction being such that when the filling 45 carrier strikes the apron 17, the weight 21 or other yielding holding means, will permit the apron to flex by drawing over the supporting rod or bar 19, substantially into the dotted line position indicated in Fig. 3, and 50 where a weight is used for this purpose, the weight will be adapted to yield upwardly on the impact of a filling carrier against the flexible apron, to thereby permit the flexible apron to draw or move over the supporting 55 bar or rod 19.

The supporting bar 18 for securing one end of the apron in the receiver is preferably located higher up in the receiver than the supporting bar or rod 19, with the result 60 that after a filling carrier has been received by the apron, and it has flexed, the filling carrier, which may still contain a working supply of filling, will roll downwardly off from the apron into the lower 65 part of the can beneath, and at such times,

even though other filling carriers may be in the lower part or compartment of the can or receiver, the gravity fall of the last ejected filling carrier will not injuriously affect the filling thereon nor unfit it for subsequent 70 use as filling in the loom.

It may sometimes happen that the filling carrier when ejected from the shuttle will be deflected by the chute 10 in a frontward direction, and to protect the filling on the carrier from injury at such times, the present invention contemplates the provision of a curtain or apron extending upwardly in the receiver from a point adjacent the flexible receiving apron against which the ejected filling carrier may strike with non-injurious 80 contact of the filling.

The curtain or apron extending from the receiving apron may be constituted as a piece of fabric, such as canvas or the like, 85 and may be attached to the receiver at the upper front portion thereof. In the present instance, the curtain or apron 22 is secured at its upper end upon a bar 23, which extends between the sides 14 of the receiver, and its lower end may, in some instances, be secured to the bar 18 with sufficient looseness, as by a loop as shown to permit the curtain to bend, the construction being such that should a filling carrier strike the curtain or apron 22 when it is ejected from the shuttle, it will cause the curtain or apron to flex, as indicated by dotted lines in Fig. 3, and the filling carrier will then drop 90 upon the receiving apron 17.

The receiving apron 17 and the curtain or apron 22 thus afford a yielding or flexing contact surface against which a filling carrier may impact when it is forcefully ejected from the shuttle, thereby avoiding any 105 injury to the delicate filling on the carrier and fitting it for use subsequently in the loom should it contain a working supply.

In the particular form of the invention shown, the curtain or apron 22 and the flexible receiving apron 17 are formed of a single piece of fabric, and the upper end of the curtain or apron 22 is provided with a loop 24 through which the upper supporting or securing bar 23 may pass to hold the upper end of the curtain or apron at the upper end of the receiver. In order to maintain the flexible receiving apron 17 secured to the support 18, when the two aprons are formed in a single piece as indicated, the combined aprons may have secured thereto adjacent the support or bar 18, a loop forming piece 25 through which the support or bar 18 may be passed.

The particular construction herein shown and described as an embodiment of the present invention is found to be practical and effective in preserving from injury the delicate filling remaining on the filling carrier or bobbin when it is forcefully ejected from 120 125 130

- the shuttle, but it is to be understood that variations may be made in the arrangement and disposition of the two aprons, the essentials in these respects being that the flexible receiving apron may be secured at one end within the receiver and have its other end under the influence of means to yieldingly hold the apron in its carrier receiving position and to flex under impact of the incoming carrier, and that the curtain or apron 22 may be so secured or held within the receiver as to cushion the impact and flex when a filling carrier is forcefully thrown frontwardly against it.
- 10 In order to conveniently remove the filling carriers from the lower compartment of the receiver, a door 26 may be made in the front wall of the receiver.
- 15 What is claimed is:—
- 20 1. A filling carrier receiver for filling replenishing looms, comprising a receptacle or can to receive filling carriers on replenishment of filling, a flexible receiving apron dividing the receptacle or can into an upper and a lower compartment, and yielding means engaged with one end of the receiving apron to normally hold the apron taut and yet yield to permit the apron to flex or bend under the impact of an ejected filling carrier.
- 25 2. A filling carrier receiver for filling replenishing looms, comprising a receptacle or can to receive filling carriers on replenishment of filling, a flexible receiving apron dividing the receptacle or can into an upper and a lower compartment, yielding means engaged with one end of the receiving apron to permit the apron to flex under the impact of an ejected filling carrier, and an apron or curtain of flexible material extending downwardly from the top of the receptacle or can towards the flexible receiving apron.
- 30 3. A filling carrier receiver for filling replenishing looms, comprising a receptacle or can to receive filling carriers as they are ejected from the loom, a flexible receiving apron dividing the receptacle or can into an upper and a lower compartment, means for securing one end of the apron to the receptacle or can, and yielding means secured to the other end of the apron for yieldingly holding the apron taut and in position to receive filling carriers as they are ejected from the loom and movable on impact of a filling carrier to permit the apron to bend.
- 35 4. A filling carrier receiver for filling replenishing looms, comprising a receptacle or can to receive filling carriers as they are ejected from the loom, a flexible receiving apron dividing the receptacle or can into an upper and a lower compartment, means for securing one end of the apron to the receptacle or can, means for yieldingly holding the other end of the apron to maintain it in

position to receive filling carriers as they are ejected from the loom, and an apron or curtain of flexible material extending upwardly from one end of the receiving apron.

5. A filling carrier receiver for filling replenishing looms, comprising a receptacle or can to receive filling carriers as they are ejected from the loom, a flexible receiving apron dividing the receptacle or can into an upper and a lower compartment, means for securing one end of the apron to the receptacle or can, means for yieldingly holding the other end of the apron to maintain it in position to receive filling carriers as they are ejected from the loom, and an apron or curtain of flexible material extending upwardly from one end of the receiving apron and secured to the receptacle or can at its upper portion to overlie the front wall of the receptacle or can.

6. In a filling carrier receiver for filling replenishing looms, the combination of a receptacle to receive filling carriers, a flexible receiving apron dividing the receptacle into an upper and a lower compartment, means for securing one end of the apron to the receptacle, a support over which the body of the apron loosely passes, and a weight connected to the free end of the apron to hold it yieldingly taut that it may flex under the impact of a filling carrier.

7. In a filling carrier receiver for filling replenishing looms, the combination of a receptacle to receive filling carriers, a flexible receiving apron dividing the receptacle into an upper and a lower compartment, means for securing one end of the apron to the receptacle, a support over which the body of the apron loosely passes, a weight connected to the free end of the apron to hold it yieldingly taut that it may flex under the impact of a filling carrier, and a flexible apron extending upwardly in the receptacle from the receiving apron.

8. A filling carrier receiver for filling replenishing looms, comprising a receptacle to receive filling carriers, a flexible receiving apron formed of fabric and having one end secured within the receptacle, a support secured to the receptacle and over which the free portion of the apron is hung, and means connected with the free portion of the apron to maintain it yieldingly in position to receive filling carriers as they are ejected from the loom.

9. A filling carrier receiver for filling replenishing looms, comprising a receptacle to receive filling carriers, a flexible receiving apron formed of fabric and having one end secured within the receptacle, a support secured to the receptacle and over which the free portion of the apron is hung, means connected with the free portion of the apron to maintain it yieldingly in position to receive filling carriers as they are ejected from the

loom, and a flexible curtain or apron extending from the top of the receptacle towards the receiving apron.

10. A filling carrier receiver for looms, comprising a can for receiving filling carriers, apron supporting rods transversely arranged between the side walls of the can, a flexible apron secured to one of the rods and

passing loosely over the other rod, and a weight connected with the free end of the ¹⁰ apron to permit the apron to flex on impact of a filling carrier.

In testimony whereof, we have signed our names to this specification:

WALLACE I. STIMPSON.
